CLAIM

We claim the ornamental design for a camera mount, as shown and described.

DESCRIPTION

FIG. 1 is a front perspective view of a camera mount showing our new design.

FIG. 2 is a rear perspective view of the camera mount shown in FIG. 1.

FIG. 3 is a front view of the camera mount shown in FIG. 1.

FIG. 4 is a rear view of the camera mount shown in FIG. 1.

FIG. 5 is a left side view of the camera mount shown in FIG. 1.

FIG. 6 is a right side view of the camera mount shown in FIG. 1.

FIG. 7 is a top view of the camera mount shown in FIG. 1; and,

FIG. 8 is a bottom view of the camera mount shown in FIG. 1.

The broken lines in the drawings depict features and portions of the camera mount that form no part of the claimed design.
